UNITED STATES PATENT OFFICE.

JOHN PRIMROSE, OF NEW YORK, N. Y., ASSIGNOR TO POWER SPECIALTY COMPANY, OF NEW YORK, N. Y., A CORPORATION OF NEW YORK.

OIL STILL.

Application filed June 19, 1920. Serial No. 390,088.

To all whom it may concern:

Be it known that I, JOHN PRIMROSE, a citizen of the United States, residing at New York, in the county and State of New York, have invented certain new and useful Improvements in Oil Stills, of which the following is a full, clear, and exact description.

The invention for which by this application I now seek protection by Letters Patent, 10 is an improvement in oil stills. The nature and purpose of the improvement may be most readily understood from the following considerations.

In a certain type or form of oil still now 15 known and used, the heat chamber is divided by a vertical bridge wall into two compartments. In that which is the more remote from the fire the heat absorbing tubes or pipes carrying the oil are arranged in one 20 main group, over which the hot gases flow downwardly, while the oil, introduced cold at the bottom of the bank, flows counter to the current of hot gases. After passing through this bank of tubes the hot oil is carried over to the bottom of a smaller bank of 25 tubes in the compartment over the fire, and the top of such bank is connected to the usual separator for taking off the vapors set free by the heat and delivering the un- 30 vaporized oil to a suitable receptacle.

This form of still is described merely as typical of all stills to which my improvement is applicable, and in such stills it has been found that the oil in the final heat 35 absorption stage, or in the second bank of coils where it is exposed to the highest temperature, does not give off all of the vapors which it should, but that a certain proportion of its volatile constituents goes over to 40 the separator with the oil.

It is to remedy this objection and to increase the yield of the volatile constituents of the oil that my present improvement was devised, and it consists in providing a return 45 passage for unvolatilized oil from the separator to the said second bank of tubes, and providing means for forcing oil to flow through said bank a second time, whereby 50 the unvolatilized parts thereof will be driven off by such second or repeated heating and a larger output of vapor thus obtained.

Specifically considered, the construction of the still is not of the essence of the invention, provided the condition herein described 55 obtains, and the invention is not therefore

limited in its scope, but consists broadly in the combination with the hottest elements of the heating surface of means for returning and forcing through the same the unvaporized oil or any desired portion of the same 60 which has already passed through them.

The invention is illustrated in the accompanying drawing, which is a view largely diagrammatic of a still of the kind described with my invention applied thereto. 65

The heating chamber 1 of the still is of the usual character, and is, in the present instance, divided by a vertical wall 2 into a forward and a rear compartment. In the latter is a bank of oil tubes or pipes 3 connected 70 in any proper and known manner for causing the oil from the source of supply 4 to flow upward through the tubes of the bank or in a direction counter to the flow of the hot gases which pass downward in this compartment on their way to the flue.

In the forward compartment is a second and smaller bank 5 of oil tubes, the lowermost row of which is connected with the uppermost row in the first bank, and such 80 smaller bank is connected by a pipe 6 to any suitable form of separator 7. The flow of oil in the second bank is not, and need not be, counter to the flow of gases, as the oil has reached a temperature when it enters the second bank that makes this unnecessary for good results.

From the separator the vapors are taken off, as by means of a pipe 8, and the unvolatilized oil by a pipe 9 at the bottom, but by 90 means of a pipe 10 any proportion of this oil that may be desired or found necessary is led to a pump 11, by which it is forced back to the connection 12 between the first and second banks of tubes, and hence caused to flow 95 again through the hottest tubes, or those of the smaller second bank.

By this means it has been found that much vapor that is not given off by the first run of oil is set free on its subsequent travel 100 through the second hot bank.

Manifestly the construction of the still as a whole is largely immaterial. As is usual in practice, it will be provided with the proper controlling valves, with means for 105 indicating the temperature of the oil and other known accessories.

What I claim is:

1. The combination with an oil still having banks or groups of tubes exposed to the 110

- 2 hot gases in different parts of their course, of means for taking off, returning to and causing to reflow through the bank or group of hottest tubes only, oil that has already 5 passed through the still, for the purpose set forth.
2. The combination with an oil still, of a furnace comprising two compartments, a bank of tubes in that compartment more remote from the fire, a bank of tubes in the compartment nearer the fire connected in series with the first, and means including an oil supplying connection intermediate the first and second banks for forcing oil that 10 has passed through and issued from the second bank back to and through said bank, for the purpose set forth.
3. The combination with an oil still having two banks of tubes and means for causing the oil to flow counter to the hot gases in the bank which is the more remote from the fire, of a separator connected with the 15 bank which is nearer the fire, a connection for oil from the separator back to the second bank and a pump therein for causing oil after having passed through said second bank and separator to reflow through the second bank, for the purpose set forth. 20
4. The combination with an oil still having two banks of tubes, one near the fire and the other more remote therefrom, means for causing the oil to flow counter to hot gases in the latter bank and in the direction of the passage of the hot gases in the former bank, a separator connected with the outlet of the 25 bank nearest the fire, and means for causing oil to flow back from the separator to the inlet of said former bank, said means being independent of the oil supplying means for the said latter bank. 30
- 35 In testimony whereof I hereto affix my signature.
- 40 JOHN PRIMROSE.
